APPARATUS FOR MIXING A LIQUID WITH
A GAS

Julian Kahn, New York, N. Y.

Application September 21, 1936, Serial No. 101,783

17 Claims. (Cl. 221—74)

This invention relates to apparatus for home use for mixing a liquid with a gas, and more particularly to apparatus for whipping cream, or for like purposes, by discharging the cream and gas mixture through a constricted orifice.

The primary object of my invention is to generally improve apparatus of the foregoing character. A more particular object is to greatly increase the operating economy of this class of apparatus, by arranging the same for successive fillings of gas from a conventional commercial cylinder of gas, in contrast with the use of a miniature bulb which can be used only once and must then be discarded. The present arrangement is not only far less costly, but results in a uniform gas pressure within the apparatus, regardless of the amount of liquid originally placed therein. A further object of my invention resides in the provision of a protective device or safety valve for preventing excess pressure within the apparatus. For purposes of economy, the protective device may be made in the form of a safety valve or pop valve, and in accordance with one of the objects and features of my invention the said device is provided with suitable indicator means, preferably means producing an audible whistle in order to announce when the apparatus has been filled with gas to the correct pressure.

Still another object of my invention is to greatly simplify the apparatus by using a single valve for two purposes, first, as an inlet valve when charging the container with gas, and second, as a constricted and somewhat labyrinthian passage for causing frothing or whipping of the cream and gas mixture. In other words, a single passage and a single valve is all that is needed for the container or vessel in which the cream and gas mixture is kept. Moreover, the said valve may be and preferably is of a simple commercially available type commonly employed in automobile tires, that is, the valve may be an ordinary tire air valve such as the commercial Schrader or Dill valve. I have found that this character of valve actually produces better whipping of the cream than is produced by more elaborate special mechanisms which have been used for this purpose and which cannot function for feeding gas into the container.

Cream whipping devices of this character have not proven popular for ordinary home use, first, because of the upkeep expense of the individual bulbs of gas previously referred to, and second, because of the high price of the apparatus itself. Moreover, the container is made of metal and is

less desirable than glass for direct contact with cream.

Further objects of my invention are to overcome the foregoing objections and to provide a small inexpensive attachment which may be detachably applied to an ordinary glass bottle such as is commonly used for soda pop, ginger ale, or the like. The bottle acts as the storage container for the cream and gas, while the attachment seals the bottle and functions to whip the cream during its discharge. In accordance with still further and more detailed objects of my invention, the quantity of whipped cream left in the nozzle or discharge passage of the apparatus is minimized to a negligible quantity; no siphon is needed; and the cream in the bottle may be exhausted to the very end, without waste.

To the accomplishment of the foregoing and other objects which will hereinafter appear, my invention consists in the apparatus elements and their relation one to the other as hereinafter are more particularly described in the specification and sought to be defined in the claims. The specification is accompanied by drawings in

Fig. 1 is a side elevation of one form of apparatus embodying features of my invention;

Fig. 2 is a section taken in elevation through the same;

Fig. 3 is a horizontal section taken in the plane of the line 3—3 of Fig. 1;

Fig. 4 shows the manner in which the bottle is charged with gas from a conventional commercial cylinder, and further shows one form of protective device disposed between the cylinder and the bottle;

Fig. 5 illustrates a modified protective device equipped with a whistle signal;

Fig. 6 illustrates a modified protective device equipped with a gas pressure indicator;

Fig. 7 is a side elevation showing the application of an attachment or adaptor to a conventional device for making charged beverages at home;

Fig. 8 is a section taken in the plane of the line 8—8 of Fig. 7;

Fig. 9 shows a modified attachment which may be used for whipping cream or for making a charged beverage; and

Fig. 10 is a section taken in the plane of the line 10—10 of Fig. 9.

Referring to the drawings and more particularly to Figs. 1, 2, and 3, the apparatus comprises a container 12 having a single tube 14 (Fig. 2) leading thereto. Tube 14 is preferably inter-

nally threaded and has screwed therein a valve 16 which may be and preferably is a conventional tire air valve. Typical commercial valves are the Schrader and the Dill valves, that here shown 5 being of the latter type. It will be noted that the valve pin 18 is faced outwardly so that gas may be supplied into container 12, the valve at that time opening automatically. This, of course, is done after a suitable quantity of cream has been 10 placed in container 12 and the container has been sealed. To produce whipped cream, it is merely necessary to tip container 12 over until tube 14 is pointed downwardly, and to thereupon slightly open valve 16, as by depressing pin 18. 15 In the present case this is done by a control lever 20 which, when pressed toward the container, opens the valve, thus permitting some of the cream to escape under pressure of the gas within the container. Because the passage 20 through the valve is constricted and complex, the cream is well whipped during its discharge. Probably the improved result which I obtain is caused by the fact that the cream and gas mixture is passed through successive constrictions, 25 first, around the end 22 of the valve; second, past the valve seat 24; third, along the valve stem 18 and through the valve spring 28; and fourth, around the guide bridge 30 of the valve pin 18. 30 Considering the arrangement in greater detail, container 12 preferably is an ordinary glass bottle such as is commonly used for soda pop, Coca Cola, ginger ale, or the like. In fact, any bottle having a standard neck 32 may be employed. The size of the bottle is without significance except that it should be substantially larger than the amount of cream to be placed therein. This, of course, simply means that any convenient size of bottle may be used, but that the 35 bottle is to be only partially filled with cream. A small ginger ale or Coca Cola bottle is especially convenient because it is easily handled and tipped.

The attachment to be placed on bottle 12 40 includes a cap or base 34 flanged at 36 and provided with a suitable sealing gasket 38. Any of a number of known clamps may be used to lock the cap on bottle 12. In the present case an operating handle 40 is pivoted on diametrically opposite sides of the cap at 42 and carries a clamp wire 44 which passes through a guide slot 46 at one side of the cap. A part of clamp wire 44 is indented at 48 to bear directly beneath the bead at the mouth of the bottle. It will be understood that the parts are so dimensioned that when handle 40 is raised, the cap is released, but that when handle 40 is forced downwardly the cap is locked in place, with gasket 38 pressed tightly against the mouth of the bottle. 45 Cap 34 is formed on its upper side with a threaded base 50 which in turn is surmounted by the threaded tube or pipe 14. This pipe is internally threaded to receive the tire air valve 16, as was previously described. It is externally 50 threaded to facilitate charging the bottle with gas, as will be subsequently described.

A discharge nozzle 52 is slid over the outside of tube 14. Nozzle 52 is held in place by a retaining member 54 the lower end of which is internally threaded to mate with the externally threaded boss 50. Retaining member 54 carries bearings 56 through which passes a pin 58. Operating lever 20 is bifurcated at 60 (Fig. 3) to pass around the retaining member 54, and an integrally formed inwardly projecting arm 62 is

fulcrumed on pin 58. The innermost tip 64 of arm 62 bears against the bottom of a recess 66 in the side of nozzle 52. Within nozzle 52 is placed a yieldable or compressible tube 68 the lower edge of which bears against the top of tube 14. Nozzle 52 also carries a valve pin depressor 70 the lower end of which is disposed directly over the upper end of valve pin 18. The parts are so proportioned that valve pin 18 is normally cleared by depressor 70, thus permitting the valve to close. However, when handle 20 is depressed toward bottle 12, the arm 64 moves nozzle 52 downwardly a slight amount against the resistance of sleeve 68. This causes the valve pin depressor 70 to depress pin 18, thereby slightly opening the valve. It will be understood that the bottle is inverted at this time, resulting in a discharge of whipped cream. (The valve pin is referred to as "depressed", although, in fact, it is raised when the bottle is inverted.) 15 20

Referring now to Fig. 4 of the drawings, the bottle is charged with a suitable and preferably inert gas, say, carbon dioxide or nitrous oxide, from a conventional commercially available cylinder of gas, the upper end of which is indicated 25 at 72. This cylinder may be small and easily handled, it being, say, of the six-ounce size. Even a three-ounce cylinder, while very small, is very many times more economical to use than the individual bulbs of gas heretofore supplied for 30 previous cream whipping devices.

Cylinder 72 has a standard outlet 74 directly beneath which is a valve the control collar of which is shown at 76. The valve is operated by rotating handle 78. These parts are all supplied 35 with and form a part of the standard commercial cylinder 72. Reverting briefly to Figs. 1 and 2, when the bottle 12 is to be newly charged some cream is poured therein, cap 34 is applied to the bottle neck and locked in place, and inlet pipe 40 14 is exposed. To expose pipe 14, the retaining member 54 is unscrewed from the threaded boss or seat 50. Nozzle 52 and handle 20 all come off with the retaining member and together form an assembly which is handled as a single piece. 45 Referring now to Fig. 4, the gas from the cylinder 72 is supplied by a short flexible pipe 80 to the tube or pipe 14 forming a part of cap 34. Pipe 80 terminates in a threaded thumb screw or coupling member 82 which may be of the type 50 commonly employed on automobile tire pumps and the like. Member 82 is simply screwed directly on the tube or pipe 14.

To prevent excessive pressure within bottle 12, any suitable protective device 84 may be interposed between cylinder 72 and bottle 12. In the present case I show a safety valve or relief valve comprising a housing 86 having a valve seat 88 on which a valve 90 bears, said valve being provided with a gasket 92. The valve is normally pushed downwardly to closed position by a compression spring 94 housed within a cap 96. The cap 96 is externally threaded, and housing 86 is internally threaded to receive the same. The tension of spring 94 is adjusted by the extent to 60 which cap 96 is screwed into the housing. This adjustment may be locked by a suitable lock nut 98. The lower end of housing 86 is provided with a threaded nipple 100 which is screwed directly into the upper end or outlet 74 on cylinder 72. 70 Pipe 80 is connected to the side of housing 86 at 102, as shown. It will be manifest that if cylinder valve 76 is kept open until an excessive pressure is reached, valve 90 is elevated against spring 94, thereby affording relief of the pres- 75

sure. The released gas escapes through opening 184 in cap 86, and, if desired, a further relief opening 186 may be provided through the side of the housing.

5 In order to eliminate undue waste of gas from cylinder 72, it is desirable to provide some form of indicator to show when the safety valve has opened. Referring to Fig. 5, I show a relief valve almost exactly like that shown in Fig. 4, except that auxiliary discharge opening 106 is eliminated and a perforated concave washer 108 is inserted between the top of cap 86 and compression spring 84. Washer 108 together with the top of cap 86 forms a whistle, and consequently when gas escapes upon opening of the safety valve, a distinct whistle is heard, thus notifying the operator that the bottle has been sufficiently charged with gas and that the main valve 76 on the cylinder should be shut off. If desired, some grooves 109 10 may be formed on the valve body to facilitate the escape of gas, this being especially desirable if the valve is not dimensioned to have considerable clearance around its periphery.

25 Referring now to Fig. 6, I show still another form of protective device comprising a safety valve 110 like those previously described but provided at one side with a pressure-gauge 112. Pressure gauge 112 is connected to the safety valve by a suitable passage schematically indicated at 114. This passage is, of course, located beneath the valve seat. The gauge is provided with an indicator needle 116, and when the needle approaches an indication on the face of the gauge dial showing the desired pressure, the main valve 30 76 (Fig. 4) of the cylinder 72 may be promptly shut off. The relief valve 110 is adjusted to open at a pressure a little higher than the desired pressure. With this arrangement it is unnecessary to waste any of the gas from the cylinder for signaling purposes.

35 Referring now to Figs. 9 and 10, I show a modified attachment in which the operating means for slightly opening the tire air valve is simpler than the operating means shown in Figs. 1, 2 and 3. In the present form of the invention, I provide a cap 120 with means 122 for detachably applying the same to a bottle 124, just as previously described. Cap 120 is surmounted by a tube or pipe 128 internally and externally threaded at 50 126, much as previously described. A tire air valve 130 is screwed into tube 128.

40 The operating means differs in comprising a nozzle 132 the base of which is enlarged to form a thumb nut 134. This is internally threaded to 45 fit over tube 128. Nozzle 132 is provided with a valve pin depressor 136. A gasket 138 is preferably disposed between the nozzle 132 and tube 128. When nozzle 132 is lightly screwed onto tube 128, depressor 136 does not quite reach the valve pin. 55 To discharge whipped cream, it is merely necessary to invert the bottle and to tighten thumb nut 134 for a fraction of a turn. This causes a slight depression of the valve pin, with consequent escape of cream. Gasket 138 limits the opening 60 of the valve, and this gasket is accordingly tightly fitted within thumb nut 134 to prevent loss. The arrangement may, of course, be made without gasket 138, but the use of a yieldable gasket is preferable in order to indicate when nozzle 65 70 75 132 has been screwed in place sufficiently to be ready for operation but without yet actually opening the valve.

75 Those features of the present invention which are directed to making it conveniently possible to use gas from a commercial cylinder rather than

from small individual bulbs, are also applicable to the charging of beverages with gas. Referring to Fig. 7 of the drawings, I show a conventional apparatus for carbonating water. Typical commercial forms of such apparatus are those called "Sparklet" and "Soda King". The apparatus comprises a bottle 140 surmounted by a cap 142 having a discharge nozzle 144 flow to which is controlled by a valve handle, not shown but located opposite support 146. Gas is supplied to the bottle through an inlet pipe 148 threaded at 150 to receive a cradle or housing (not shown) which carries an individual gas bulb or tube and forces the same against a perforating needle located inside of inlet pipe 148. When the cradle is not in use, the thread 150 may, if desired, be covered by a cap 152.

10 In accordance with my invention, I provide a fitting or attachment 154 the nature of which is best shown in Fig. 8. This attachment is enlarged 15 at its lower part to form a thumb nut 156 which is internally threaded at 158 to fit over the thread 150 of the bottle. An internal skirt or flange 160 may be provided adapted to bear against a gasket 162 in inlet 148, thereby insuring a gas-tight connection. Attachment 154 is reduced in diameter and externally threaded at 164 to receive the coupling 82 of gas supply hose 80. The latter is schematically indicated in broken lines in Fig. 7, and, of course, is identical with the corresponding parts shown in Fig. 4. Moreover, it will be understood that a protective device like those shown in Fig. 4, 5, or 6, is combined with hose 80 in order to limit the pressure supplied to the bottle 140.

15 I prefer to thread the attachment 154 internally, as is indicated at 166, thereby adapting the same to receive a tire air valve 168. This forms an extra seal against escape of gas from bottle 140. It will be understood, however, that the attachment may also be used without the tire air valve 168, reliance then being placed on the valve which is ordinarily provided within inlet 150 of the bottle. One advantage of using the tire air valve is to adapt the attachment for bottles of this 20 character of a somewhat more old-fashioned type in which gas inlet 148 is not provided with a valve. In such case the tire air valve 168 becomes the sole valve for sealing the bottle against escape of gas after hose 80 has been removed.

25 Before concluding, I may point out that an attachment such as I have illustrated in Figs. 9 and 10, may also be used for charging beverages. The admission of gas is accomplished just as previously described. The bottle is then shaken 30 and the carbonated beverage may be released by opening the tire air valve, much as previously described, although for the present purpose the valve is preferably opened more widely than is the case when whipping cream. While the beverage is 35 constricted somewhat during its discharge, this is not undesirable and, in fact, has the advantage of "fizzing" the beverage, much like special commercial fizzers sometimes used to liven up 40 ordinary bottled beverages.

45 It is believed that the construction and operation, as well as the many advantages of my improved apparatus for mixing a liquid with a gas, or, more particularly, for whipping cream, will be apparent from the foregoing detailed description thereof. The necessary apparatus is small, simple and inexpensive to manufacture. A single valve is used both for inlet of gas and for discharge of the mixture, and this valve may be 50 an inexpensive tire air valve. Despite the cheap- 55 60 65 70 75 80 85 90 95 100

ness of the valve used, the whipped cream produced is of excellent quality. The gas is obtained cheaply by drawing the same from standard commercial cylinders, rather than from special individual bulbs of gas. The mixture is kept in glass, which is desirable for sanitary reasons, and also because the amount of liquid in the container may be observed at any time. The container is particularly inexpensive, it being an ordinary bottle of standard type. Danger of breaking the bottle by excessive pressure is eliminated by a suitable protective device, and wastage of gas from the cylinder may also be guarded against. It is unnecessary to use a siphon, although apparatus like the present may, of course, be designed to use a siphon. The pressure to which the bottle is filled is uniform regardless of the quantity of liquid placed in the bottle. (When using individual bulbs, the ultimate pressure varies with the amount of liquid in the bottle because the content of the bulb is predetermined.) The present apparatus permits the whipping of a small amount of cream, and even the last few drops of cream in the bottle may be utilized. Moreover, the length of nozzle beyond the valve is particularly small, and the quantity of whipped cream exposed beyond the valve is therefore a minimum. This is desirable because the whipped cream in the nozzle is exposed to air and may tend to spoil. There is very little contact of the cream with metal. When using a small bottle, the apparatus occupies but little space in a refrigerator. In addition to whipping cream, the apparatus may be used to carbonate water or other beverages; to make a pancake mixture; and for other purposes which will readily suggest themselves.

It will be apparent that while I have shown and described my invention in preferred forms, many changes and modifications may be made in the structures disclosed, without departing from the spirit of the invention, defined in the following claims. For example, the cap may be made large in diameter to fit a large mouthed bottle, specifically a standard quart or pint milk bottle. A tube may be provided depending from the cap, to act as a siphon tube, but in such case the valved pipe and the cream discharge nozzle are preferably shaped to discharge the cream sidewardly or downwardly, rather than upwardly. The elimination of the siphon tube, however, makes for convenience, simplicity, and cheapness.

I claim:

1. In an apparatus for whipping cream (or for like purposes) by mixing the cream with a gas under pressure and discharging the same through a constricted passage, a conventional tire air valve including a slender tube having its inner end acting as a valve seat, a pin extending through said tube at both ends, a valve part secured to the inner end of said pin for bearing against the inner end of said tube, and a return spring coiled about said pin for urging the valve to closed position, the passage through said tube around said pin being a comparatively constricted passage, and the passage between said valve part and valve seat being even more highly constricted when the valve pin is only slightly depressed, said tire air valve acting as an inlet valve when filling the apparatus with gas, and also acting as a constricted passage-way when discharging the cream and gas mixture, a discharge nozzle for guiding the whipped cream from the tire air valve, and means accessible

outside the discharge nozzle for slightly depressing the pin of the tire air valve.

2. Apparatus for the whipping of cream or for like purposes, said apparatus comprising a container having a discharge tube leading therefrom, a conventional tire air valve including a slender tube having its inner end acting as a valve seat, a pin extending through said tube at both ends, a valve part secured to the inner end of said pin for bearing against the inner end of said tube, and a return spring coiled about said pin for urging the valve to closed position, the passage through said tube around said pin being a comparatively constricted passage, and the passage between said valve part and valve seat being even more highly constricted when the valve pin is only slightly depressed, said tire air valve being screwed into said tube with the valve pin projecting outwardly, and control means accessible outside the discharge tube for depressing the valve pin in order to cause the valve to act as a constricted discharge passageway.

3. Apparatus for the whipping of cream or for like purposes, said apparatus comprising a container having a gas inlet tube leading thereto, a conventional tire air valve including a slender tube having its inner end acting as a valve seat, a pin extending through said tube at both ends, a valve part secured to the inner end of said pin for bearing against the inner end of said tube, and a return spring coiled about said pin for urging the valve to closed position, the passage through said tube around said pin being a comparatively constricted passage, and the passage between said valve part and valve seat being even more highly constricted when the valve pin is only slightly depressed, said tire air valve being screwed into said tube, with the valve pin projecting outwardly, whereby the valve acts as an inlet valve when charging the container with gas, additional control means for slightly depressing the valve pin in order to permit the valve to act as a constricted discharge passageway during the ejection of the cream and gas mixture, and a yieldable stop member made of rubber or the like, against which said control means presses and which must be compressed by said control means before said valve pin opens, thereby preventing accidental opening of the valve.

4. Apparatus for whipping cream or for like purposes, said apparatus comprising a container which is fully enclosed except for a single pipe leading therefrom, a conventional tire air valve including a slender tube having its inner end acting as a valve seat, a pin extending through said tube at both ends, a valve part secured to the inner end of said pin for bearing against the inner end of said tube, and a return spring coiled about said pin for urging the valve to closed position, the passage through said tube around said pin being a comparatively constricted passage, and the passage between said valve part and valve seat being even more highly constricted when the valve pin is only slightly depressed, said tire air valve being screwed in said pipe and so faced as to hold gas in the container, a valve pin depressor capable of only limited movement, and an operating handle for moving the depressor in order to cause a limited depression of the valve pin.

5. Apparatus for whipping cream or for like purposes, said apparatus comprising a container which is fully enclosed except for a pipe leading therefrom, a conventional tire air valve includ-

ing a slender tube having its inner end acting as a valve seat, a pin extending through said tube at both ends, a valve part secured to the inner end of said pin for bearing against the inner end of said tube, and a return spring coiled about said pin for urging the valve to closed position, the passage through said tube around said pin being a comparatively constricted passage, and the passage between said valve part and valve seat being even more highly constricted when the valve pin is only slightly depressed, said tire air valve being screwed into said pipe and so faced as to hold gas in the container, a discharge nozzle removably applied over said pipe outside said valve, a valve pin depressor fixedly secured in said nozzle, and an operating handle for moving the nozzle relative to the pipe in order to cause a limited depression of the valve pin.

6. A household attachment comprising a cap 20 removably applicable to a glass bottle having a standard neck, a pipe leading through said cap, a valve in said pipe so faced as to hold gas within the bottle, a discharge nozzle removably applied over said pipe, a valve pin depressor in said discharge nozzle, and an operating handle for moving the depressor against the valve pin.

7. A household attachment comprising a cap 30 removably applicable to a glass bottle having a standard neck, a single pipe leading through said cap, a tire air valve of standard type including a slender tube having its inner end acting as a valve seat, a pin extending through said tube at both ends, a valve part secured to the inner end of said pin for bearing against the inner end of said tube, and a return spring coiled about said pin for urging the valve to closed position, the passage through said tube around said pin being a comparatively constricted passage, and the passage between said valve part and valve seat 40 being even more highly constricted when the valve pin is only slightly depressed, said tire air valve being screwed into said pipe and so faced as to hold gas within the bottle, a valve pin depressor, and an operating handle for moving the depressor against the valve pin.

8. A household attachment comprising a cap 50 removably applicable to a glass bottle having a standard neck, a pipe leading through said cap, a tire air valve of standard type screwed into said pipe and so faced as to hold gas within the bottle, a discharge nozzle removably applied over said pipe, a valve pin depressor fixedly secured in said discharge nozzle, and an operating handle for moving the discharge nozzle relative to the pipe until the valve pin is depressed.

9. A household attachment comprising a cap 60 having releasable attachment means making the same removably applicable to a bottle, a pipe projecting from said cap, a valve in said pipe so faced as to hold gas within the bottle, a discharge nozzle reciprocably positioned over said pipe, a retaining member detachably secured to said cap for holding the nozzle in place over the pipe, an operating handle movably mounted on said retaining member and arranged to depress the nozzle relative to the pipe and retaining member, and a valve depressor secured to said nozzle for opening the valve upon operation of the handle.

10. An attachment or accessory for whipping cream or for like purposes, said attachment comprising a cap having releasable attachment means making the same removably applicable to a glass bottle having a standard neck, a tire 75 threaded pipe projecting from said cap, a tire

air valve of conventional type screwed into said pipe and so faced as to hold gas within the glass bottle, a discharge nozzle reciprocably positioned over said pipe, a retaining member screwed onto said cap for holding the nozzle in place over the pipe, an operating handle pivotally mounted on said retaining member and arranged to depress the nozzle relative to the pipe and retaining member, and a valve pin depressor secured to said nozzle for limitedly depressing the valve pin 10 upon operation of the handle.

11. An attachment or accessory for whipping cream or for like purposes, said attachment comprising a cap having releasable attachment means making the same removably applicable 15 to a glass bottle having a standard neck, an internally and externally threaded pipe projecting from said cap, a tire air valve of conventional type screwed into said pipe and so faced as to hold gas within the glass bottle, a discharge 20 nozzle having an enlarged rotatable base internally threaded to be received over the external thread of the pipe, and a depressor in said nozzle arranged to slightly or limitedly depress the pin of the air valve when the nozzle is 25 screwed all the way onto the pipe.

12. Apparatus for the whipping of cream or for like purposes, said apparatus comprising a container having a gas inlet tube leading thereto, a conventional tire air valve including a 30 slender tube having its inner end acting as a valve seat, a pin extending through said tube at both ends, a valve part secured to the inner end of said pin for bearing against the inner end of said tube, and a return spring coiled about 35 said pin for urging the valve to closed position, the passage through said tube around said pin being a comparatively constricted passage, and the passage between said valve part and valve seat being even more highly constricted when 40 the valve pin is only slightly depressed, said tire air valve being screwed into said tube, with the valve pin projecting outwardly, whereby the valve acts as an inlet valve when charging the container with gas, additional means for slightly 45 depressing the valve pin in order to permit the valve to act as a constricted discharge passageway during the ejection of the cream and gas mixture, a conventional commercially available cylinder of gas, a protective device secured to 50 the discharge opening of the cylinder, and an outlet from said protective device adapted to be detachably secured over the aforesaid gas inlet tube, said protective device operating to limit the maximum pressure which may be applied to 55 the apparatus from the gas cylinder.

13. Apparatus for whipping cream or for like purposes, said apparatus comprising a container which is fully enclosed except for a pipe leading therefrom, a valve in said pipe so faced as to 60 hold gas in the container, a discharge nozzle removably applied over said pipe outside said valve, a valve depressor in said nozzle, an operating handle for moving the nozzle relative to the pipe in order to cause opening of the valve, 65 a conventional commercially available cylinder of gas, a protective device secured to the discharge opening of the cylinder, an outlet from said protective device adapted to be secured over the aforesaid pipe when the nozzle is removed, 70 said protective device operating to limit the maximum pressure which may be applied to the container from the gas cylinder, and indicator means to indicate when the desired container pressure has been reached.

14. A household attachment comprising a cap removably applicable to a glass bottle having a standard neck, a pipe leading through said cap, a valve in said pipe so faced as to hold gas within the bottle, a discharge nozzle removably applied over said pipe, a valve pin depressor in said discharge nozzle, an operating handle for moving the depressor against the valve pin, a conventional commercially available cylinder of gas, a protective device secured to the discharge opening of the cylinder, an outlet from said protective device adapted to be secured over the aforesaid pipe, said protective device operating to limit the maximum pressure which may be applied to the bottle from the cylinder. 10
15. A household attachment comprising a cap removably applicable to a glass bottle having a standard neck, a pipe leading through said cap, a tire air valve of standard type screwed into said pipe and so faced as to hold gas within the bottle, a discharge nozzle removably applied over said pipe, a valve pin depressor fixedly secured in said discharge nozzle, an operating means for moving the discharge nozzle relative to the pipe until the valve pin is depressed, a protective device adapted to be secured to the discharge opening of a conventional commercially available cylinder of gas, and an outlet from said protective device adapted to be secured over the aforesaid pipe, said protective device operating to limit the maximum pressure which may be applied to the bottle from the gas cylinder. 20
16. In combination, a conventional commercially available cylinder of gas, a protective device secured to the discharge opening of the cylinder, an outlet from said protective device 25
- adapted to be secured over the gas inlet tube of a household apparatus for mixing a gas and a liquid, said protective device operating to limit the maximum pressure which may be applied to the apparatus from the gas cylinder, said protective device comprising a safety valve or pop valve including a movable valve loaded by a compression spring the tension of which is adjusted to desired value, and means causing gas released upon opening of the valve to produce a distinguishing whistle. 30
17. Apparatus for charging a beverage with a gas, said apparatus including a fitting adapted to be received over the conventional threaded gas inlet pipe of ordinary home carbonating units, 15 a tire air valve including a slender tube having its inner end acting as a valve seat, a pin extending through said tube at both ends, a valve part secured to the inner end of said pin for bearing against the inner end of said tube, and a return spring coiled about said pin for urging the valve to closed position, the passage through said tube around said pin being a comparatively constricted passage, and the passage between said valve part and valve seat being even more highly 25 constricted when the valve pin is only slightly depressed, said tire air valve being disposed in said fitting, a conventional commercially available cylinder of gas, a pressure-limiting protective device connected directly to the outlet of the cylinder, and a flexible discharge pipe from said protective device adapted to be detachably secured to the aforesaid fitting, whereby the beverage container may be repeatedly filled from the single cylinder of gas. 30

35 JULIAN KAHN.

Disclaimer

2,170,531.—*Julian Kahn, New York, N. Y. APPARATUS FOR MIXING A LIQUID WITH A GAS. Patent dated Aug. 22, 1939. Disclaimer filed July 1, 1949, by the inventor.*

Hereby enters this disclaimer to claims 1, 2, 3, and 4 of said patent.
[Official Gazette August 2, 1949.]

14. A household attachment comprising a cap removably applicable to a glass bottle having a standard neck, a pipe leading through said cap, a valve in said pipe so faced as to hold gas within the bottle, a discharge nozzle removably applied over said pipe, a valve pin depressor in said discharge nozzle, an operating handle for moving the depressor against the valve pin, a conventional commercially available cylinder of gas, a protective device secured to the discharge opening of the cylinder, an outlet from said protective device adapted to be secured over the aforesaid pipe, said protective device operating to limit the maximum pressure which may be applied to the bottle from the cylinder. 10
15. A household attachment comprising a cap removably applicable to a glass bottle having a standard neck, a pipe leading through said cap, a tire air valve of standard type screwed into said pipe and so faced as to hold gas within the bottle, a discharge nozzle removably applied over said pipe, a valve pin depressor fixedly secured in said discharge nozzle, an operating means for moving the discharge nozzle relative to the pipe until the valve pin is depressed, a protective device adapted to be secured to the discharge opening of a conventional commercially available cylinder of gas, and an outlet from said protective device adapted to be secured over the aforesaid pipe, said protective device operating to limit the maximum pressure which may be applied to the bottle from the gas cylinder. 20
16. In combination, a conventional commercially available cylinder of gas, a protective device secured to the discharge opening of the cylinder, an outlet from said protective device 25
- adapted to be secured over the gas inlet tube of a household apparatus for mixing a gas and a liquid, said protective device operating to limit the maximum pressure which may be applied to the apparatus from the gas cylinder, said protective device comprising a safety valve or pop valve including a movable valve loaded by a compression spring the tension of which is adjusted to desired value, and means causing gas released upon opening of the valve to produce a distinguishing whistle. 30
17. Apparatus for charging a beverage with a gas, said apparatus including a fitting adapted to be received over the conventional threaded gas inlet pipe of ordinary home carbonating units, 15 a tire air valve including a slender tube having its inner end acting as a valve seat, a pin extending through said tube at both ends, a valve part secured to the inner end of said pin for bearing against the inner end of said tube, and a return spring coiled about said pin for urging the valve to closed position, the passage through said tube around said pin being a comparatively constricted passage, and the passage between said valve part and valve seat being even more highly 25 constricted when the valve pin is only slightly depressed, said tire air valve being disposed in said fitting, a conventional commercially available cylinder of gas, a pressure-limiting protective device connected directly to the outlet of the cylinder, and a flexible discharge pipe from said protective device adapted to be detachably secured to the aforesaid fitting, whereby the beverage container may be repeatedly filled from the single cylinder of gas. 30
